[57] CLAIM

The ornamental design for wrist-watch, as shown.

DESCRIPTION

FIG. 1 is a right, front and top perspective view of a wristwatch showing my new design;

FIG. 2 is a top plan view;

FIG. 3 is a front elevational view;

FIG. 4 is a rear elevational view;

FIG. 5 is a right side elevational view;

FIG. 6 is a left side elevational view;

FIG. 7 is a bottom plan view thereof.

The broken line showings of a watch face in FIGS. 1 and 2 are environmental only and form no part of the claimed design.
